UNITED STATES PATENT OFFICE.

ARTHUR F. ROLFE, JOSEPH H. ROLFE, ABIAL W. ROLFE, AND CHARLES M. ROLFE, OF PENACOOK, NEW HAMPSHIRE.

COIN-ENVELOPE.

SPECIFICATION forming part of Letters Patent No. 426,331, dated April 22, 1890.

Application filed May 11, 1889. Serial No. 310,394. (No model.)

To all whom it may concern:

Be it known that we, ARTHUR F. ROLFE, JOSEPH H. ROLFE, ABIAL W. ROLFE, and CHARLES M. ROLFE, citizens of the United States, residing at Penacook, in the county of Merrimac and State of New Hampshire, have invented certain new and useful Improvements in Coin-Envelopes, of which the following is a specification.

10 The object of this invention is to provide convenient means for the transmission of small coin through the mail; and the invention consists in an envelope having divisions or pockets for holding and keeping separate 15 various coins, and means for closing the entrance to said pockets ready for mailing, as fully set forth in the following specification and claim, and clearly illustrated in the accompanying drawings, forming an inseparable 20 part thereof, of which—

Figure 1 shows one of our improved envelopes when only partially completed. Fig. 2 shows a side view as when completed and closed up, a few coins being represented by 25 dotted lines therein. Fig. 3 is a detached view of the part forming the divisions of our improved envelope.

Similar reference-letters designate like parts.

30 It is our purpose to render our improved envelope useful either to be inclosed within an ordinary letter-envelope or to affix to it an address and postage-stamp for independent transmission; hence its outer dimensions are 35 smaller than a medium-sized letter-envelope. The outside of the envelope is preferably cut in one piece from a tough paper, and when folded at a forms the front and back, respectively, A A' . One of the parts A A' will be 40 cut wider and longer than the other for the purpose of closing and sealing the envelope. In the drawings these extensions are provided

upon the front A , as represented at a' a^2 a^3 . The partitions forming the coin-pockets C are cut from suitable thick paper, cloth, or other 45 material, preferably in one piece, consisting of a strip D , running centrally from end to end of an envelope, having lateral branches E extending to its sides. These are gummed both sides and placed upon the part A , as 50 seen in Fig. 1. The part A' is then folded over upon the partitions D E , and the end extension a' , after being gummed, is also folded over upon the part A' , and the envelope is 55 then ready for use. The side flaps a^2 a^3 are 60 gummed and allowed to dry without being stuck down; but they may be folded over as are the flaps of any ordinary envelope, and after inserting any coins desired these may be moistened and stuck down, when our improved envelope will be ready for mailing. The part A' , if desired, may be scalloped on 65 its sides, as indicated by dotted lines in Fig. 2, for facilitating the entrance of a coin in either pocket C .

Having described our improvements, what we claim, and desire to secure by Letters Patent, is—

A coin-envelope having its ends normally closed and provided with interposing divisions forming two rows of pockets having their orifice at either side of said envelope, and side flaps adapted for folding over to close the same.

In testimony whereof we affix our signatures 75 in presence of two witnesses.

ARTHUR F. ROLFE.
JOSEPH H. ROLFE.
ABIAL W. ROLFE.
CHARLES M. ROLFE.
